ATTORNEY.

UNITED STATES PATENT OFFICE.

HAROLD O. BIGNEY, OF ATTLEBORO, MASSACHUSETTS, ASSIGNOR TO SIDNEY O. BIGNEY, OF ATTLEBORO, MASSACHUSETTS.

DESIGN FOR AN EMBLEM.

41,033.

Specification for Design.

Patented Dec. 13, 1910.

Application filed October 24, 1910. Serial No. 588,934. Term of patent 7 years.

To all whom it may concern:

Be it known that I, HAROLD O. BIGNEY, a citizen of the United States, residing at Attleboro, in the county of Bristol and State of Massachusetts, have invented a certain new, original, and ornamental Design for an Emblem, of which the following is a specification.

In the accompanying drawings which form a part of this specification the figure is a front view of an emblem embodying my design.

I claim:

The ornamental design for an emblem, as shown.

HAROLD O. BIGNEY.
